UNITED STATES PATENT OFFICE.

FRANK T. AHERN, OF NEW YORK, N. Y., ASSIGNOR TO FERDINAND STRAUSS, OF YONKERS, NEW YORK.

PUSH-TOY JIGGER.

1,251,458.

Specification of Letters Patent.

Patented Jan. 1, 1918.

Application filed February 28, 1917. Serial No. 151,385.

To all whom it may concern:

Be it known that I, FRANK T. AHERN, a citizen of the United States of America, residing at New York city, county and State 5 of New York, have invented certain new and useful Improvements in Push-Toy Jiggers, of which the following is a full, clear, and exact description.

This invention relates to improvements in 10 dancing or jiggling toys, the object being to provide a jointed figure mounted upon a wheeled support or platform and connected to some moving part of the running gear of the support so as to cause the figure to 15 dance or jig while the support is being moved, preferably pushed. Special means are provided to prevent that part of the running gear from operating the figure, when the wheeled support is moved in a 20 direction contrary to the direction intended to operate the figure.

I will now describe my invention in detail, the novel features of which I will point out in the appended claims, reference being 25 had to the accompanying drawing, forming part hereof, wherein Figure 1 is a side elevation of an embodiment of my invention, the push handle being broken off; Fig. 2 is an enlarged sectional view of the operating 30 mechanism for the figure; Fig. 3 is an enlarged plan view of the disk which forms part of the operating mechanism; Fig. 4 is an enlarged edge view of the disk, a portion 35 of the shaft which carries the figure, being also illustrated; Fig. 5 is an enlarged fragmentary sectional diagrammatic view of the mechanism for preventing the actuation of the figure, the section being taken on a line 5—5 in Fig. 1. As herein embodied, my 40 invention comprises a platform or support 6 having two wheels 7, and two wheels 8, one only of each of said wheels being shown. The front wheels 7 are carried by a block 9, the rear wheels 8 being connected to a 45 rotary axle 10 supported by a casing 11 secured to the platform 6.

Within the casing 11 and secured to the axle 10, I located a spider 12 consisting of a plurality of radially disposed arms 13 to 50 impinge upon, raise, and rotate a disk 14 secured to a vertical rod or shaft 15, to which a figure 16 is preferably firmly secured, the arms 17 of the figure being preferably pivotally secured to the body 18 at 55 18^a. The legs of the figure consist of sec-

tions 19 and 20 pivoted together at 21, the sections 19 being pivoted to the body of the figure at 22.

The rod or shaft 15 is slidably supported by the platform 6 and casing 11 and is 60 adapted for vertical movement. To simulate jiggling, motion is imparted to the figure 16 by moving the shaft 15 vertically; the said shaft being moved vertically by the rotation of the spider 12. As will be seen 65 in Fig. 2 the arms 13 impinge upon the disk 14 from the dotted position to the full line position, thereby causing the shaft 15 and the figure carried thereby to rise. When an arm leaves the disk 14 the shaft and figure 70 will drop. During the rotation of the spider, which is caused by pushing the platform by means of the handle 23, the figure will rise and fall rapidly, causing the jointed legs to assume various positions 75 simulating dancing or jiggling. To impart to the figure a rotary movement as well as a vertical movement, I form the disk 14 so as to include a plurality of angularly disposed blades 24, that is to say, angularly 80 disposed relative to the axis of the shaft 15. Owing to the angular disposition of the said blades, the disk 14 will be partly rotated as well as raised, each time an arm 13 strikes one of said blades. It is believed that this 85 effect will be apparent and needs no further description.

To prevent the wheels 8 from rotating, thereby preventing the actuation of the spider 12, when the support is moved in a 90 direction opposite to the direction intended to operate the figure 16, I provide in this instance a coil-spring 24 having a projecting end 25 normally engaging the spokes 26 of one of the wheels 8 (see Fig. 5). When 95 moved in the proper direction, the spokes 26 will brush by the end 25 of the spring 24. Should the wheels 8 tend to rotate in the opposite direction, a spoke of an adjacent wheel will strike the end 25 of the spring 24 100 and force it against a pin 27, thereby preventing further rotation of the wheel. The spring 24 is supported by a post 28 on the platform 6. The object of permitting rotation of the wheels in one direction only is to 105 prevent the arms 13 from forcing the disk 14 downwardly or in other words from striking it from above.

What I claim as my invention is:

1. The combination of a support, rota- 110

table ground wheels therefor, a dancing figure carried by said support, operating means for regularly rotating and lifting said figure, and means operable by the said wheels 5 to actuate the figure operating means.

2. The combination of a support, rotatable ground wheels therefor, a dancing figure carried by said support, operating means for said figure, means operable by the said 10 wheels to actuate the figure operating means, and means to permit the rotation of said wheels in one direction only.

3. A support mounted on wheels, in combination with a dancing figure carried there- 15 by and mounted on a vertically movable rotatable rod, a disk provided with inclined vanes arranged to give said rod both a vertical and a rotary movement when said vanes are struck from below, a rotary spider ar- 20 ranged to be driven by one of said ground wheels and to strike upward with its spokes against the lower side of said vanes successively.

4. The combination of a support, rotatable wheels on which it is mounted, a dancing figure carried by said support, operating means for said figure, means operable by the said wheels to actuate the figure operating means, and a yieldable latch to permit 25 the rotation of the wheels in one direction only.

5. The combination of a support, rotatable wheels on which it is mounted, a dancing figure carried by said support, operating means 30 for said figure, means operable by the wheels of said support to actuate the figure operating means, a spring carried by said support

having a projecting end engaging the spokes of an adjacent wheel operating said figure, and a stop-pin to prevent the yielding of the 40 projecting end of said spring when the wheel tends to rotate in a direction opposite to the direction intended to operate the figure.

6. The combination of a platform, a vertically movable post carried thereby, a jointed figure secured to said post, a disk carried by said post with vanes inclined for operation when struck from below to lift and rotate said figure, a rotatable axle carried by said 45 platform, ground wheels secured to said axle, means carried by the axle arranged to strike the under surface of said disk and raise and simultaneously turn the movable post, said means being incapable of such operation 50 when striking said disk from above, and means for preventing this latter contact.

7. The combination of a platform, a vertically movable post carried thereby, a jointed figure secured to said post, a disk carried by 55 said post, a rotatable axle carried by said platform, wheels secured to said axle, means carried by the axle arranged to strike the under surface of said disk and raise the movable post during the rotation of the 60 axle, and means to permit the rotation of said axle in one direction only.

Signed at New York city, N. Y., this 15th day of February, 1917.

FRANK T. AHERN.
